WATER TUBE BOILER

Ermin Pokorný, Prague, Czechoslovakia

Application February 4, 1937, Serial No. 124,128
In Czechoslovakia February 11, 1936

3 Claims. (Cl. 122—321)

This invention relates to water tube boilers with natural water circulation, that is the water circulates without the aid of pumping means, for all steam pressures.

- 5 In steep tube boilers, of which use is frequently made, the nests of tubes are substantially acted on directly by the radiated heat in the furnace chamber, while the remaining surfaces are heated substantially only by the contact of the flue gases.
- 10 In order to bring about the water circulation, a certain number of the tubes are constructed as descending tubes, through which the water passes from the upper container into the lower container, and these tubes are generally either 15 accommodated in the rear flues or arranged outside the flues.

The vaporisation capacity increases with the steam pressure, because the higher the pressure is, the lower the corresponding vaporisation heat 20 is. The degree of the vaporisation capacity of a boiler is also influenced by the speed of the circulating water, but sufficient attention is frequently not devoted to this speed.

In many high-pressure boilers, the natural 25 speed of the water is artificially increased by pumping. A great water speed in the tubes decreases the deposit of fur on the inner walls and increases the vaporisation capacity. When the vaporisation capacity is great, there is set up in 30 the tubes a greater steam speed, which causes water and consequently moisture of the vapour to be carried along. In the descending pipes, the water flows downwards and the steam generated rises, whereby disturbances may be brought about 35 in the circulation when the vaporisation capacity is fairly great.

An object of the present invention is to provide a water tube boiler with an intensive natural circulation, this boiler being furnished with an upper collector for steam and water carried along therewith which is arranged outside the heating chamber and which is connected by tubes with a preferably vertical cylindrical container arranged outside the heating chamber on any side 45 of the boiler. In this container, a water and steam chamber is provided. More than one container may be employed if desired.

By this arrangement, a definite and intensive circulation, practically dry steam, and the possibility of a correct removal of mud and reduction of the fur deposit are afforded.

The above and further objects of the invention will be hereinafter described with reference to the 55 constructional embodiment of a boiler according

to the invention illustrated in the accompanying drawing, in which:

Figure 1 shows diagrammatically a cross section through the boiler, and

Figures 2 and 3 are a side elevation and a plan 5 view respectively of the boiler.

A high speed in the tubes is produced by employing tubes having a suitable cross section. If the diameter and the length of each tube are made such that the speed of the generated steam 10 in the tube is greater than the speed at which the small steam bubbles rise in the water, then the bubbles combine to form large bubbles which fill a certain part of the tube and force the water up before them. For this purpose the length of 15 the water tubes should be so selected with reference to their diameter that the volume of steam generated per second in each tube fills at least one seventh of the volume of the tube.

If only so much steam has been generated that 20 it fills a part of the tube, the small bubbles rise separately to the top and the water sinks about them. If a larger bubble rising only owing to buoyancy be formed, the water flows downwards 25 past this bubble along the walls of the tube. Such is the case in heated descending or reflux tubes.

A further important feature of the invention resides in that the heating gases are guided into 30 contact with the water tubes from the very lowest part of said tubes, which generally is not the case, because the flow of gases does not accurately follow the path determined by the transverse walls of the flue, so that a part of the heating 35 surface often remains unutilised.

From the lower water drum 1 (Figure 1) water tubes 2 extend, which pass obliquely through the furnace chamber and rise to the upper collector 3 arranged outside the brickwork. The mixture of steam and water which has been forced into 40 the collector 3 from the tubes 2 by the heating of said tubes flows out of the collector 3 through the tubes 4 into a vertical container (or a plurality of containers) arranged laterally of the brickwork, in which container the steam accumulates at the top and the water at the bottom, 45 the water returning through the tubes 6 into the water drum 1 of the boiler. Above the lower inclined part of the water tubes 2, a steam superheater 10 is arranged. The dot-and-dash lines 50 show the approximate course of the heating gases, which practically cover the entire heating surface of the water tubes 2. Steam and a quantity of water which is several times greater when referred to the weight of the steam, pass into the 55

collector 3. The steam is therefore moist and is thus carried away together with the water from the collector 3 into the container 5 through a plurality of horizontal tubes 4 which are larger than the tubes 2. The water is separated from the steam in the tubes 4 and flows at the bottom of the tubes, while the steam flows at the top. Upon entrance into the container 5, the speed of the steam is reduced owing to the much greater cross section, and the last traces of water are separated therefrom. Consequently, dry steam passes into the superheater 10, which is very important in particular at high temperatures, as otherwise various salts and similar substances emanating from the water carried along travel along with the steam and are deposited in the steam turbine or other apparatus connected to the boiler.

The water in the container 5 slowly sinks and the solid constituents contained in the water have sufficient time to be deposited on the bottom of the container, from whence they can be readily removed at F.

Behind the boiler water economisers 8 and 9 (Figure 2) may be provided. The boiler according to the invention is suitable principally for plants operating with a fluctuating withdrawal of steam, as it has a very large water and vapour chamber, so that upon sudden withdrawal of steam a very considerable pressure fluctuation does not occur.

What I claim and desire to secure by Letters Patent of the United States is:

1. A water tube boiler having a definite intensive natural water circulation for all steam pressures, comprising a furnace chamber, a lower water drum disposed in said chamber, an upper collector arranged outside the furnace chamber, steeply inclined water tubes passing through the furnace chamber and connecting said water drum to the upper collector, at least one container provided outside the furnace chamber, the upper portions of said container constituting a steam chamber and the lower portion a water chamber, a tube connecting the upper collector to the steam chamber of the container, and means connecting the water chamber of the container to the water drum, the outlets of the water tubes in the upper collector being outside the furnace chamber and above the inlet of the tube connecting the collector to the steam chamber of the container to prevent any back flow of water through the water tubes.

2. A water tube boiler having a definite intensive natural water circulation for all steam pressures, comprising a furnace chamber, a lower

water drum disposed in said chamber, an upper collector arranged outside the furnace chamber, steeply inclined water tubes passing through the furnace chamber and connecting said water drum to the upper collector, at least one container provided outside the furnace chamber, the upper portions of said container constituting a steam chamber and the lower portion a water chamber, a plurality of tubes connecting the upper collector to the steam chamber of the container, and means connecting the water chamber of the container to the water drum, the outlets of the water tubes in the upper collector being outside the furnace chamber and above the inlets of the tubes connecting the collector to the steam chamber of the container to prevent any back flow of water through the water tubes, the diameter and the length of said second-mentioned tubes being such that the steam passing through these tubes has sufficient time to separate from the water before it reaches the steam chamber of the container so that the water will fall down into the water chamber of said container.

3. A water tube boiler having a definite intensive natural water circulation for all steam pressures, comprising a furnace chamber, a lower water drum disposed in said chamber, an upper collector arranged outside the furnace chamber, steeply inclined water tubes passing through the furnace chamber and connecting said water drum to the upper collector, at least one container provided outside the furnace chamber, the upper portions of said container constituting a steam chamber and the lower portion a water chamber, a plurality of tubes connecting the upper collector to the steam chamber of the container, and means connecting the water chamber of the container to the water drum, the outlets of the water tubes in the upper collector being outside the furnace chamber and above the inlets of the tubes connecting the collector to the steam chamber of the container to prevent any back flow of water through the water tubes, the diameter and the length of said second-mentioned tubes being such that the steam passing through these tubes has sufficient time to separate from the water before it reaches the steam chamber of the container, so that the water will fall down into the water chamber of the said container and the water tubes being of such a diameter and length that the volume of steam generated per second in each water tube fills at least one seventh of the volume of the tube.
